UNITED STATES PATENT OFFICE.

PEARL HILES AND JEREMIAH J. MCNERNEY, OF ST. LOUIS, MISSOURI.

SAFETY-PIN.

1,071,919.

Specification of Letters Patent.

Patented Sept. 2, 1913.

Application filed October 26, 1912. Serial No. 727,901.

To all whom it may concern:

Be it known that we, PEARL HILES and JEREMIAH J. MCNERNEY, citizens of the United States, residing at St. Louis, State of Missouri, have invented certain new and useful Improvements in Safety-Pins; and we do hereby declare the following to be a full, clear, and exact description of the invention, such as will enable others skilled in the art to which it appertains to make and use the same.

This invention relates to pins, and more particularly to pins for identification purposes, and has as its object to provide an identification device which will consist of an ordinary safety pin, and certain elements attached thereto, producing a device for the purpose mentioned, which will be simple and which will be extremely cheap, using as it does an ordinary safety pin and an additional single element stamped from sheet metal.

Other objects and advantages will be apparent from the foregoing specification and it will be understood that changes may be made in the specific structure shown and described without departing from the spirit of the invention as defined by the appended claims.

In the drawings forming a portion of this specification and in which like numbers of reference indicate similar parts of the several views, Figure 1 is an elevational view of the complete device. Fig. 2 is a perspective view, showing the device opened to receive an identification slip. Fig. 3 is a plan of the blank from which the swinging member is formed, and Fig. 4 is a detailed perspective view of the swinging member detailed.

Referring now to the drawings, the present invention comprises a safety pin including the back bar 2, at one end of which there is located the keeper 3, and which, at its opposite end is bent into the usual loop, integral with which there is formed the spring pin bar 1 movable into and out of engagement with the keeper. The loop above referred to is indicated at 4 in the drawings.

A retaining member adapted to receive in conjunction with the back bar 2 an identification slip, is provided, and is formed from a blank of sheet metal including a rectangular body portion 5 having laterally ex-

tending ears 6 and 7 at one end. The body portion is bent upon itself longitudinally, thus bringing the ears 6 and 7 into parallel relation, and, as indicated, the centers of these ears are stamped inwardly as indicated at 8. The resultant projections are adapted for engagement within the inclosure of the coil 4, and the swinging member is disposed upon the back bar of the pin with the side portions 5' of the blank 5 at opposite sides of the bar, the projections 8 extending into the loop and forming in conjunction therewith a pivot for the clamping member. In use, the identification of the wearer of the device is written upon a slip of paper which is folded and inserted between the sides 5', in the space indicated at 10, the retaining member having been raised as shown in Fig. 2. The retaining member is then moved into the position shown in Fig. 1 when the slip of paper having the identification thereon will be firmly held in place. The resilience of the metal from which the retaining device is formed results in sufficient friction between the moving parts to hold the member closed against the back bar of the pin.

What is claimed is:

1. The combination with a safety pin, of means for holding an identification slip thereto, said means consisting of a member having side portions lying at opposite sides of the back bar of the pin and having ears at one end lying at opposite sides of the loop of the pin, said ears having their central portions stamped inwardly within the inclosure of the loop for pivotal movement of the member with respect to the pin and for the prevention of disengagement of the member bodily from the pin.

2. The combination with a safety pin, of means for holding an identification slip thereto, said means consisting of a retaining member adapted for co-action with a portion of the pin to hold the identification slip therebetween, and means co-acting with the loop of the pin for pivotally connecting the holding member thereto.

3. The combination with a safety pin, of means for holding an identification slip thereto, said means comprising a metallic blank bent longitudinally upon itself and disposed with its side portions at opposite sides of the back bar of the pin, said side portions at one end having a pair of parallel

lel ears disposed over and at opposite sides of the loop of the safety pin, and means carried by the ears and co-acting with the top for preventing disengagement of the holding member from the pin and for permitting pivotal movement of the holding member with respect to the pin.

In testimony whereof, we affix our signatures, in the presence of two witnesses.

PEARL HILES.
JEREMIAH J. McNERNEY.
